UNITED STATES PATENT OFFICE.

ALBERT BERNHARD WALTHER, OF JAMESTOWN, NEW YORK, ASSIGNOR TO DAHLSTROM METALLIC DOOR COMPANY, OF JAMESTOWN, NEW YORK, A CORPORATION OF NEW YORK.

METALLIC DOOR.

1,242,283.

Specification of Letters Patent.

Patented Oct. 9, 1917.

Application filed March 6, 1912. Serial No. 681,963.

To all whom it may concern:

Be it known that I, ALBERT BERNHARD WALTHER, a citizen of the United States, and resident of Jamestown, in the county 5 of Chautauqua and State of New York, have invented certain new and useful Improvements in Metallic Doors, of which the following is a specification.

My invention relates to metallic doors 10 and more particularly to such as are constructed of sheet metal having hollow stiles at opposite sides of a metallic or other panel.

The primary object of my invention is the production of a door formed of sheet metal 15 and having its seams at the edges of the door so as to form an air-tight double sheet metal door through which neither smoke, hot air or gas can pass.

Another object of my invention is the provision of a door which is principally formed of two metallic sheets extending the full length and width of the door and being connected by seams only at the edges of the door.

25 A still further object is the provision of edge seams which are invisible when the door is finished with a suitable finishing coating.

Still further objects is the provision of a 30 double lock seam reinforced to stiffen the edge of the door; to provide improved means of securing the rails to the panel portions of the door; to provide means of securing the door hinges thereto; and to 35 otherwise improve the construction of metallic doors, as will appear hereinafter.

To these ends the invention consists in the novel features of construction and arrangement of parts to be hereinafter described 40 and more particularly pointed out in the subjoined claims.

In the drawings:

Figure 1 is a side elevation of a door constructed according to my invention.

45 Fig. 2 is an enlarged horizontal section taken on line 2—2, Fig. 1.

Fig. 3 is an enlarged horizontal section taken on line 3—3, Fig. 1.

Fig. 4 is a sectional perspective view of 50 one corner of the door.

Fig. 5 is an enlarged vertical section taken on line 5—5, Fig. 1.

Fig. 6 is a sectional perspective view of one corner of the door, without the upper

rail and closure plates at the upper edge of 55 the door.

Fig. 7 is a horizontal section of a door embodying my invention with a glass panel inserted therein.

Referring now to the drawings in detail 60 like letters of reference refer to like numbers in the several figures.

The door, in the preferred construction, has two main portions formed of metallic sheets A, B which extend the full length and 65 width of the door, each sheet being rolled or otherwise provided with a central panel depression C which extends the full length of the sheet, the sides of said panel depressions being defined by ornamental moldings 70 D rolled in the sheets and therefore integral therewith. These two sheets of metal are spaced apart to provide hollow stiles E and spaced panel members. Between the panel members a filling F of asbestos or 75 other non-inflammable material is interposed while the door stiles may be filled with ground cork or other suitable material having the quality of deadening sound.

The edges of the stiles or door are formed 80 by bending the longitudinal or marginal portions of the two sheets into substantially U-shape, as at G, and at right angles to the faces of the sheet of which they form part (or approximately so). An interlocking 85 strip H is provided at each edge of the door which has locking connection with the U-shaped marginal portions of the sheets, each of said strips having its marginal portions rebent upon its intermediate portion, as at 90 h, and fitted between the two transversely-disposed members g of the coöperating U-shape portions. These interlocking strips occupy the entire transverse dimension between the side walls of the stiles and are 95 placed in position by slipping them into the stiles from either end. When properly positioned they are rolled together with the U-shaped marginal portions of the sheet so as to provide a solid edge of laminated form, 100 thus making a rigid and strong connection. In this manner a door is provided which is formed principally of two sheets of metal so interlocked at their edges by double lock seams which stiffen the edges of the door 105 and enable the door to be made of lighter gage material. The double lock seams also lessen the possibility of damage at the edges

of the door so that at all times a perfectly tight fit is assured in the door opening and by reason of the sides of the door being formed in the main of two sheets of metal 5 extending the entire length and width of the door, all face seams are eliminated so that assurance is had that neither smoke, hot air, or gas can penetrate.

- Near one side edge of the door, openings 10 I are formed in one of the stiles, in each of which openings is placed one of the members of a door hinge J, the hinge being offset, as at j, to bring the projecting portion flush with the adjacent edge of the door. 15 One of the side walls of each opening I is in line with the inner face of the interlocking strip H so that when the hinge members are thrust into the door they bear against said interlocking strip, and in order to provide a suitable bearing for the opposite side 20 of the hinge members and with a view of stiffening the door at its hinge edge, a reinforcing strip K is fitted into the stile with its edges in contact with opposite sides of 25 the stile and with one of its faces in contact with the hinge members. This reinforcing strip is preferably made of comparatively thick bar-iron so as to provide a solid foundation for screws L which are passed 30 through openings formed in the double lock seam and through registering openings in the hinge members and which screws take into the reinforcing strip K.

While the door in the main comprises two 35 metallic sheets, it is finished at the upper and lower edges by rails M, each rail comprising two metallic sheets m arranged at opposite sides of the door and having their inner marginal portions rolled to form moldings N corresponding with the moldings D 40 between the panel and stiles. The moldings N are cut at their end to fit moldings D and the ends of the flat portions of the sheets m 45 thus making completely finished connections at these points.

The depressed portions C of the two sheets A, B are recurved at their upper and lower ends, as at O, for the purpose of stiffening 50 the edges of the panels formed by such depressed portions and also for the purpose of providing a space between the two sheets of each rail at their outer edges. In said spaces, channel bars P are inserted for the 55 purpose of stiffening the outer edges of the rails, which channel-bars extend into the open upper and lower ends of the stiles E and likewise serve to stiffen said ends. Facing plates p are placed against the edges 60 of the channel bar P with their outer faces flush with the edges of the rails and the end edges of the stiles, said facing plates being fastened to the channel-bars P by means of screws R. Said channel-bars are riveted, 65 welded, or otherwise suitably secured to the

metallic sheets forming the opposite sides of the rails and to the ends of the stiles. The moldings at the inner marginal portions of the rails securely stiffen the sheets forming the rails at such points, and between said moldings and the channel-bars P, further means for stiffening the rails are provided, which constitute clips S welded or otherwise secured to the inner faces of the two metallic sheets forming each rail and Z-bars T riveted or otherwise secured to the depressed or panel portions of the two sheets A, B. Said Z-bars have their outer marginal portions engaged or interlocked with the clips S. In this manner the rail at the upper and lower ends of the door are well stiffened, resulting in a very rigid door.

In the modification shown in Fig. 7, the stiles U of the door are formed of a single sheet of metal having their marginal portions rebent into U-shape, as at u, which U-shape portions receive the marginal portions of a stiffening bar V similar to the construction shown in the preceding figures. The inner edge of each stile has a straight portion W, and an inwardly extending portion or molding w forming an abutment for a pane of glass X held in place by a securing molding x. It is to be understood that the inner edges of the rails X are formed like those of the stiles, and that the rails are secured to the stiles at their ends in any approved manner.

It is apparent therefore, that certain features of my invention may as readily be embodied in a door having a glass panel as one having a metallic panel, and it is also to be understood that certain features of my invention may be used without other features thereof. Doors vary as to style and form and, therefore, do not admit in all cases of the use of all the features of this invention.

Having thus described my invention, what I claim is:

1. A sheet metal door having hollow stiles and an interposed panel formed of two sheets of metal connected together at the edges of the door, each sheet being bent or rolled longitudinally to form one-half of each stile and an interposed panel portion, said panel portions having free upper and lower ends recurved upon themselves, and rails formed of sheet metal fitted on the panel portions between the stiles, a channel-iron fitting into the outer portions of said rails and the ends of said stiles, and a facing plate bearing against the edges of each channel-iron and secured thereto.

2. A sheet metal door having a hollow stile and an interposed panel, each stile having the marginal portions of the metal forming the same bent at right angles to the sides of the stile and thence rebent to form U-shaped portions, and an interlocking strip

within each stile having its marginal portions rebent to interlock with the U-shaped portions of the metal forming the stile, each interlocking strip extending from side wall 5 to side wall of the stile and with said U-shaped portion forming an edge wall having four thicknesses of metal co-extensive with the thickness of the door.

3. A sheet metal door having the longitudinal marginal portions of its sheet or sheets bent into substantially U-form and at right angles to the face of the door, and an interlocking strip connecting said U-

formed portions and extending from upper to lower end of the door with its longitudinal edges in contact with the side walls of the stile, thereby providing a solid edge consisting of a plurality of layers of metal composed only of said interlocking strip and said metal sheet or sheets. 15

In testimony whereof I have set my hand in the presence of two subscribing witnesses.

ALBERT BERNHARD WALTER.
